US00D839895S

(12) **United States Design Patent** (10) **Patent No.:** **US D839,895 S**
Dell (45) **Date of Patent:** **** Feb. 5, 2019**

(54) **DISPLAY SCREEN WITH GRAPHICAL USER INTERFACE**

(71) Applicant: **Robert Bosch GmbH**, Stuttgart (DE)

(72) Inventor: **Hermann Dell**, München (DE)

(73) Assignee: **Robert Bosch GmbH**, Stuttgart (DE)

(**) Term: **15 Years**

(21) Appl. No.: **29/572,370**

(22) Filed: **Jul. 27, 2016**

(30) **Foreign Application Priority Data**

Jan. 27, 2016 (EM) 002961672

(51) **LOC (11) Cl.** **14-04**

(52) **U.S. Cl.**

USPC **D14/486**

(58) **Field of Classification Search**

USPC D14/485-495; D12/572, 579, 581-586,
D12/590-591

CLAIM

The ornamental design for a display screen with graphical user interface, as shown and described.

DESCRIPTION

The FIGURE is a front view of a display screen with graphical user interface showing my new design.

The broken lines shown in the FIGURE illustrate portions of the display screen with graphical user interface that form no part of the claimed design.

1 Claim, 1 Drawing Sheet
